UNITED STATES PATENT OFFICE

GABRIEL HAWIE, OF BRIDGEPORT, CONNECTICUT, ASSIGNOR TO THE HAWIE MANUFACTURING COMPANY, OF BRIDGEPORT, CONNECTICUT

HOSE SUPPORTER

Application filed November 7, 1930. Serial No. 494,144.

This invention relates to improvements in hose supporters or the like having metal loops or slotted members through which the webbing is slidable.

The primary object of the invention is to provide an adjustable buckle slide, exhibiting as little metal as possible at the front, being as thin as practicable, having no rough edges to irritate or injure the wearer's flesh, and which will also save labor in stringing or threading the webbing.

In the conventional buckle slides, the web has to be threaded through the slide several times, and this is a time consuming and tedious operation, whereas in my construction, a single threading only is required.

Another object is to furnish a buckle slide for hose supporters, comprising a clamp bar connected to one end of the webbing and having a projecting lip which clamps another portion of the webbing to one of the cross bars of the single loop. A structure of this character will not only act to maintain the metal out of contact with the skin of the wearer and allow the webbing to be readily adjusted, but after the parts are in operative position, the harder the pull on the webbing, the greater will the clamp bar press on the webbing to prevent the same from accidentally slipping.

With the foregoing objects outlined and with other objects in view which will appear as the description proceeds, the invention consists in the novel features hereinafter described, in detail, illustrated in the accompanying drawings, and more particularly pointed out in the appended claims.

In the drawings,

Fig. 1 is a front perspective view of my improved device.

Fig. 2 is a similar view of one form of the improved clamp bar attached to an end of the webbing.

Fig. 3 is a view like Fig. 2, but with the webbing reversed to show the teeth of the clamp bar penetrating the webbing.

Fig. 4 is a sectional view of a detail on the line 4—4 of Fig. 1.

Fig. 5 is a view similar to Fig. 2, but showing a modification in which the project-

ing lip of the clamp bar is provided with teeth.

Fig. 6 is a view similar to Fig. 4 but showing the clamp bar lip in the same plane as the front side of the clamp bar.

Referring to the drawings, 6 designates a conventional garter loop, and 7 the webbing attached to the same. One end of this webbing is secured as shown at 8 to my improved clamp bar which forces a portion of the webbing against a single loop 9 which forms the other element of my improved combination.

The loop member which has a single transverse slot 10, consists either of a single metal stamping or may be formed of a piece of wire.

The clamp bar or clip member is made of sheet metal and bent into U or V shape, before the end of the webbing is inserted between its opposite sides, and said sides are pressed toward one another. The front side 11 of the clip member is higher than the rear side 12 thereof, and has its upper edge bent forwardly to form a transverse lip 13 that is adapted to clamp a portion of the web 75 against one of the bars of the loop member 9. If preferred, the edge of the lip may be provided with teeth, as shown at 14 in Fig. 5.

It is preferred to use some means on the clip member to penetrate the webbing to prevent detachment of the clamp bar from the end of the webbing. Any suitable means may be used for this purpose. For example, the upper edge of the short side 12 may be provided with teeth 15 which bite into the web, 85 as shown in Fig. 4.

In manufacturing such a construction, an end of the webbing is inserted between the two sides of the U or V-shaped clip member, and these sides are squeezed together in a suitable press to securely clamp the web. The loop member 9 is then threaded on to the free end of the webbing and pulled down against the clip member or clamping bar. The garter loop 6 is then threaded on to the free end of the web, and finally, the free end of the web is then brought up over the front side 11 of the clip member, and under the front bar of the loop 9 to complete the garter.

From that time on, for adjustment pur-

poses, it is only necessary to pull the clip member 8 slightly away from the loop 9, so that the intermediate portion 16 of the webbing may freely slide through the loop. When the adjustment has been finished, the clip 8 is moved back against the loop, and now its forwardly projecting lip will clamp the intermediate portion 16 of the webbing against the front bar of the loop. From this time on, any stretching of the webbing will cause the lip 13 to more firmly clamp the webbing to the loop and prevent any sliding action.

Those skilled in the art will recognize that this adjustable means is much simpler than those heretofore known, and much easier to use for adjustment purposes, and yet, after an adjustment has been made, the parts will hold just as securely as if the webbing was threaded several times through the loop member.

It will also be noted that the upper part of the front 11 of the clip member is wider than the slot 10 of the loop member, so as to form projecting lugs 17 that bear against the ends of the loop member.

Instead of having the clamp bar lip project forwardly I may arrange the parts as shown in Fig. 6, in which the webbing 21 is provided at one end with a clamp bar 22 of a single thickness of metal having tongues 22a struck therefrom, to form a back wall. The upper end of this bar forms a projecting lip 23 which is in the same plane as the plate forming the bar, and acts to clamp the webbing against the upper part of the loop 20.

While I have disclosed what I now consider to be a preferred embodiment of the invention in such manner that its construction, operation and advantages may be readily understood by those skilled in the art, I am aware that changes may be made in the details disclosed, without departing from the spirit of the invention, as expressed in the claims.

What I claim and desire to secure by Letters Patent is:

1. In a device of the character described, a loop member having a transverse slot, a plural thickness of webbing extending through the slot, and a clip member secured to one end of the webbing and having a projecting lip clamping another portion of the webbing against a part of the loop member, the clip member being separate from and unconnected to the loop member.

2. In a device of the character described, a loop member having a transverse slot, a plural thickness of webbing extending through the slot, and a clip member secured to one end of the webbing and having a projecting lip clamping another portion of the webbing against a part of the loop member, the clip member being of substantially U-shape in cross section and having walls of

different heights, said lip forming the extremity of the highest one of the walls, the clip member being separate from and unconnected to the loop member.

3. In a device of the character described, a loop member having a transverse slot, a plural thickness of webbing extending through the slot, and a clip member secured to one end of the webbing and having a projecting lip clamping another portion of the webbing against a part of the loop member, the ends of the lip portion of the clip member bearing against the ends of the loop member, the clip member being separate from and unconnected to the loop member.

4. In a device of the character described, a loop member having a transverse slot, a plural thickness of webbing extending through the slot, and a clip member secured to one end of the webbing and having a projecting lip clamping another portion of the webbing against a part of the loop member, said clip member being of substantially U-shape in cross section and having front and rear walls, one of the walls having teeth projecting into the end of the web, the clip member being separate from and unconnected to the loop member.

5. In a device of the character described, a loop member having a transverse slot, a plural thickness of webbing extending through the slot, and a clip member secured to one end of the webbing and having a projecting lip clamping another portion of the webbing against a part of the loop member, said lip having teeth to penetrate the portion of the web which it clamps, the clip member being separate from and unconnected to the loop member.

6. In a device of the character described, a loop member having a transverse slot, a plural thickness of webbing extending through said slot, and a clip member secured to an end of the webbing and including a wall having a projecting lip in the same plane therewith and clamping a portion of the webbing against said loop member, the clip member being separate from and unconnected to the loop member.

In testimony whereof, I have signed this specification.

GABRIEL HAWIE.
